UNITED STATES PATENT OFFICE.

FRANK C. BONNET, OF CHICAGO, ILLINOIS.

TALKING-MACHINE.

1,356,594.

Specification of Letters Patent. Patented Oct. 26, 1920.

Application filed August 7, 1919. Serial No. 315,858.

To all whom it may concern:

Be it known that I, FRANK C. BONNET, a citizen of the United States, residing at Chicago, in the county of Cook and State 5 of Illinois, have invented new and useful Improvements in Talking-Machines, of which the following is a specification.

This invention relates to talking machines wherein a plurality of record disks are 10 brought into playing position, one after the other, and the invention has for its object to provide a novel and improved means for automatically effecting the transfer of the disks from a supply stack to the turn table 15 of the machine.

The object stated is attained by means of a combination and arrangement of parts to be hereinafter described and claimed, and in order that the same may be better understood, reference is had to the accompanying 20 drawings forming a part of this specification.

In the drawings,

Figure 1 is an elevation of the machine; 25 Fig. 2 is a plan view with parts broken away;

Fig. 3 is an enlarged section on the line 3—3 of Fig. 1, and

Fig. 4 is a detail in perspective.

Referring specifically to the drawings, 30 the invention is shown applied to a talking machine employing a flat record disk 10 which is supported, when in playing position, on a turn table 11. The usual swinging tone arm 12 carries a sound box 13 equipped with a stylus or needle 14 which travels in the grooves of the record disk. These parts are all of well known design, and hence need not be described in detail.

40 A fragment of the cabinet of the machine is shown at 15. Fig. 1 shows two records on the turn table, the bottom one having been played, and the needle now engaging the top one and playing the same. A means 45 has been provided for supporting a stack of records above the turn table, from which stack one record after the other is lowered to the turn table to be played. This stack of records is indicated by the reference character 10^a.

The top of the cabinet 15 supports uprights 16 carrying at the top a rectangular open frame 17. The turn table spindle 18 on which the records 10 are centered has an 55 upward extension as shown on which the records 10^a are impaled. The stack of rec-

ords is supported by the following means: A rod 19 carried by the frame 17 extends across the latter and is so positioned that it comes beneath the stack 10^a close to the edge 60 of the bottom record as shown in Fig. 2. Diametrically opposite the rod 19 the stack is supported by a feed wheel having four arms 20, 21, 22 and 23, respectively. This feed wheel is horizontally positioned and 65 carried by a rotatable vertical shaft 24. At one of the corners of the frame 17 is mounted a plate 25 carrying a post 26 on which is strung a number of leather strips 27 which are inserted between the records 10^a to 70 slightly space the same, these strips being so located that the spacing is close to the feed wheel.

The feed wheel is designed to be given a turn in a clock-wise direction after a record 75 is played, and thereby release the bottom record 10^a of the stack. It will be noted that the advancing edges of the arms 20 and 22 are tapered to an edge so that they may slide under the stack smoothly. The feed 80 wheel is normally positioned so that the arm 20 (or the arm 22) is beneath the stack and supporting the same on one side of its center by engaging the bottom record, the support on the other side being the rod 19. The 85 arms 21 and 23 are slightly higher than the arms 20 and 22, and the spacing of the arms is such that just before the arm 20 leaves the bottom of the stack, the arm 21 comes beneath the second record from the bottom of 90 the stack. When the arm 20 clears the stack, the bottom record drops and the stack is now supported by the arm 21. As the feed wheel continues to turn, the arm 21 leaves the stack and the arm 22 comes under the 95 stack to support it, and the parts are now in position for another operation, the feed wheel having made a half revolution. The records 10^a are sufficiently loose on the spindle 18 so that they may tilt and slide off 100 the rod 19 when they are released by the feed wheel. The spacing of the records by the strips 27 assures the entry of the arms 21 and 23 between the two bottom records. The released bottom record 10^a slides down, 105 the spindle 18 and comes into playing position on the turn table 11 or on top of the records 10 already thereon.

The following means are provided for controlling the operation of the feed wheel: 110

The tone arm 12 has an integral extension 28 at its outer end carrying the sound

box 13. To the extremity of this extension is fastened a line 29, and the extension rests on an arm 30 pivoted at 31 to a bracket 32 mounted on top of the cabinet 15. To the 5 arm 30 is attached a lifting line 33 extending upward to and over a pulley 34 carried by the frame 17.

At 35 is shown a housing containing a 10 spring motor or other motor of any suitable kind for driving the feed wheel, the shaft 24 of the latter extending into the housing. The shaft 24 is belted, as shown at 36, or otherwise operatively connected to a spindle 37 having at its upper end a crank arm 38 to which the line 33 is attached. On the 15 lower end of the spindle 37 is a disk 39 having a peripheral notch 40. Adjacent to the disk 39 is a lever 41 pivoted at 42 to the housing 35 and drawn toward the periphery of the disk by a spring 43. The lever 41 has a tooth 44 adapted to enter the notch 40, and the line 29 is connected to the lever. When the tooth 44 is in the notch 40, the 20 feed wheel shaft 24 is locked and prevented 25 from turning, and upon swinging the lever to withdraw the tooth, the shaft is released and the feed wheel starts to turn to allow another record to drop to the turn table 11 as hereinbefore described.

30 The operation of the mechanism may be summarized as follows: Fig. 2 shows the tone arm 12 at the beginning of the record groove, and as the selection is played, the tone arm moves toward the center of the 35 record disk 10, carrying with it the extension 28, which latter draws on the string 29 and pulls the lever 41 to release the motor 35. The length of the string is such that the motor is released when the tone arm 40 reaches the end of its record trip. At this time the extension 28 rests on the arm 30 near its outer end, and as said arm swings up, due to the lifting line 33 operated by the motor, it will be understood from Figs. 45 1 and 3 that the tone arm is elevated and 50 swung outwardly at the same time, thus clearing the path for the next record disk about to drop from the elevated stack. The tone arm swings outwardly a sufficient 55 distance so as to be completely out of the path of the descending record disk. The crank arm 38 makes one complete revolution at each operation. During one half of its 60 revolution it draws on the line 33 to swing the lifting arm 30 upwardly to the dotted line position shown in Fig. 3, and during the 65 next half of the revolution of the crank arm the line 33 is paid out to allow the arm 30 to swing down and again lower the tone arm 70 to playing position. The feed of the new record occurs when the tone arm has been 75 elevated and swung laterally to its limit, clear of the descending record disk. When the tone arm is again positioned in playing 80 position, the disk 39 has made a complete 85

revolution, and as the tooth 44 is now again opposite the notch 40, and the line 29 is slack, the tooth enters the notch, and the feed motion is arrested.

Where an electric motor drive is provided, a suitable arrangement of switches 70 will be provided.

The frame has a depending guide wall 45 along the curved edge of which the tone arm 12 slides when it is elevated and 75 lowered. The curve of this edge is such that when the tone arm descends and clears the guide wall, it will have been swung inwardly with respect to the record disk 10 on the turn table 11 such a distance as to 80 automatically place the needle at the proper starting point on the record disk. The descent of the tone arm is not violent, as it is restrained by the line 33, and the needle engages the record disk gently and without 85 damage.

The housing 35 is supported by standards 46 rising from the top of the cabinet 15, and by a strap 47 connected to one of the 90 uprights 16.

I claim:

1. The combination with a talking machine having a record supporting turn table and a swinging tone arm; of a spindle rising from the center of the turn table on 95 which a stack of records is adapted to be impaled, supporting means for the stack engaging the bottom thereof on one side of its center, a feed wheel on the other side, said wheel having arms one of which normally engages the bottom record of the stack, and the other one coming beneath the record next to the bottom one when the first mentioned arm is withdrawn from the bottom of the stack, driving means for the 100 feed wheel, a lock for the driving means, and means actuated by the movement of the tone arm for controlling the lock.

2. The combination with a talking machine having a record supporting turn table and a swinging tone arm; of a spindle rising from the center of the turn table on 110 which a stack of records is adapted to be impaled, supporting means for the stack engaging the bottom thereof on one side of its center, a feed wheel on the other side, said wheel having arms one of which normally engages the bottom record of the stack, and the other one coming beneath the record 115 next to the bottom one when the first mentioned arm is withdrawn from the bottom of the stack, driving means for the feed wheel, means actuated by the movement of the tone arm for controlling the feed wheel, and a connection between said driving 120 means and the tone arm for elevating the latter.

3. The combination with a talking machine having a record supporting turn table and a swinging tone arm; of a spindle ris- 130

ing from the center of the turn table on which a stack of records is adapted to be impaled, supporting means for the stack engaging the bottom thereof on one side of 5 its center, a feed wheel on the other side, said wheel having arms one of which normally engages the bottom record of the stack, and the other one coming beneath the record next to the bottom one when the first 10 mentioned arm is withdrawn from the bottom of the stack, driving means for the feed wheel, means actuated by the movement of the tone arm for controlling the feed wheel, a connection between said driving means 15 and the tone arm for elevating the latter, and a guide engageable by the tone arm for swinging the same laterally to starting position.

4. The combination with a talking machine having a record supporting turn table 20 and a swinging tone arm; of a spindle rising from the center of the turn table on which a stack of records is adapted to be impaled, supporting means for the stack 25 engaging the bottom thereof on one side of its center, a feed wheel on the other side, said wheel having arms one of which normally engages the bottom record of the stack, and the other one coming beneath the 30 record next to the bottom one when the first mentioned arm is withdrawn from the bottom of the stack, means adjacent to the feed wheel and independent thereof for spacing the records in the stack, said means being 35 adjustable for insertion between the records, driving means for the feed wheel, and means actuated by the movement of the tone arm for controlling the feed wheel.

5. The combination with a talking machine having a record supporting turn table 40 and a swinging tone arm; of a spindle rising from the center of the turn table on which a stack of records is adapted to be impaled, supporting means for the stack 45 engaging the bottom thereof on one side of its center, a feed wheel on the other side, said wheel having arms one of which normally engages the bottom record of the stack, and the other one being higher than 50 the first mentioned arm and coming beneath the record next to the bottom one when said first mentioned arm is withdrawn from the bottom of the stack, means adjacent to the feed wheel and independent 55 thereof for spacing the records in the stack, said means being adjustable for insertion between the records, driving means for the feed wheel, and means actuated by the movement of the tone arm for controlling 60 the feed wheel.

6. The combination with a talking machine having a record supporting turn table 65 and a swinging tone arm; of means for supporting a plurality of records in a stack above the turn table, means for delivering

the records one after the other to the turn table from the bottom of the stack, driving means for said delivering means, a lock for the driving means, and means actuated by the movement of the tone arm for controlling the lock. 70

7. The combination with a talking machine having a record supporting turn table and a swinging tone arm; of means for supporting a plurality of records in a stack 75 above the turn table, means for delivering the records one after the other to the turn table from the bottom of the stack, driving means for said delivering means, a lock for the driving means, means actuated by the 80 movement of the tone arm for controlling the lock, and means for elevating the tone arm.

8. The combination with a talking machine having a record supporting turn table 85 and a swinging tone arm; of means for supporting a plurality of records in a stack above the turn table, means for delivering the records one after the other to the turn table from the bottom of the stack, means 90 actuated by the movement of the tone arm for controlling such delivery, means for elevating the tone arm, and a guide engageable by the tone arm for swinging the same laterally to starting position. 95

9. The combination with a talking machine having a record supporting turn table and a swinging tone arm; of means for supporting a plurality of records in a stack above the turn table, means for delivering 100 the records one after the other to the turn table, driving means for said delivering means, a lock for the driving means, means actuated by the movement of the tone arm for controlling the lock, and means for 105 swinging the tone arm clear of the disks before their delivery to the turn table, said means operating after the delivery of the disks to restore the tone arm to playing position. 110

10. The combination with a talking machine having a record supporting turn table and a swinging tone arm; of means for supporting a plurality of records in a stack 115 above the turn table, means for delivering the records one after the other to the turn table, driving means for said delivering means, a lock for the driving means, means actuated by the movement of the tone arm for controlling the lock, and means actuated by the aforesaid driving means for swinging the tone arm clear of the disks before their delivery to the turn table, said means operating after the delivery of 120 the disks to restore the tone arm to playing 125 position.

11. The combination with a talking machine having a record supporting turn table and a swinging tone arm; of means for supporting a plurality of records in a stack 130

- above the turn table, means for delivering the records one after the other to the turn table, driving means for said delivering means, a lock for the driving means, means actuated by the movement of the tone arm for controlling the lock, means for swinging the tone arm clear of the disks before their delivery to the turn table, said means operating after the delivery of the disks to restore the tone arm to playing position, and means engageable by the tone arm for guiding the same to its starting place on the record.
12. The combination with a talking machine having a record supporting turn table and a swinging tone arm; of means for supporting a plurality of records in a stack above the turn table, means for delivering the records one after the other to the turn table, driving means for said delivering means, a lock for the driving means, means actuated by the movement of the tone arm for controlling the lock, and a vertically swinging member engageable with the tone arm for swinging the same clear of the disks before their delivery to the turn table, said member being actuated by the aforesaid driving means and operating after the delivery of the disks to restore the tone arm to playing position.
13. The combination with a talking machine having a record supporting turn table and a swinging tone arm; of means for supporting a plurality of records in a stack above the turn table, means for delivering the records one after the other to the turn table, driving means for said delivering means, a lock for the driving means, means actuated by the movement of the tone arm for controlling the lock, a vertically swinging member engageable with the tone arm for swinging the same clear of the disks before their delivery to the turn table, and for restoring the tone arm to playing position after delivery of the disks, a crank arm actuated by the aforesaid driving means, and an actuating connection between the crank arm and the swinging member.
14. The combination with a talking machine having a record supporting turn table and a swinging tone arm; of means for supporting a plurality of records in a stack above the turn table, means for delivering the records one after the other to the turn table, driving means for said delivering means, a lock for the driving means, means actuated by the movement of the tone arm for controlling the lock, a vertically swinging member engageable with the tone arm for swinging the same clear of the disks before their delivery to the turn table, and for restoring the tone arm to playing position after delivery of the disks, a crank arm actuated by the aforesaid driving means, an actuating connection between the crank arm and the swinging member, and means engageable by the tone arm for guiding the same to its starting place on the record.

In testimony whereof I affix my signature.
FRANK C. BONNET.
